DESIGN FOR A BUTTON

Leonard R. Carley, Watertown, Conn., assignor to The Patent Button Company, Waterbury,
Conn., a corporation of Connecticut

Application November 16, 1938, Serial No. 81,143

Term of patent 14 years

To all whom it may concern:

Be it known that I, Leonard R. Carley, a citizen of the United States, residing at Watertown, in the county of Litchfield and State of Connecticut, have invented a new, original, and ornamental Design for Buttons, of which the following is a specification, reference being had to the accompanying drawing, forming part thereof, in which:—

Fig. 1 is a top plan view of a button on an enlarged scale showing my new design; and
Fig. 2 is a side elevation thereof.

I claim:
The ornamental design for a button, as shown.

LEONARD R. CARLEY.
